UNITED STATES PATENT OFFICE.

RAY DOUGLASS, OF DEER PARK, NEW YORK.

BOBBIN-WINDING APPARATUS FOR SEWING-MACHINES.

1,387,368.

Specification of Letters Patent.

Patented Aug. 9, 1921.

Application filed April 21, 1915. Serial No. 22,735.

To all whom it may concern:

Be it known that I, RAY DOUGLASS, a citizen of the United States, residing at Deer Park, in the county of Suffolk and State of New York, have invented new and useful Improvements in Bobbin-Winding Apparatus for Sewing-Machines, of which the following is a specification.

This invention relates to sewing machines.

In the use of such machines bobbins are usually employed which are operated by the mechanism of the machine so as to pass the thread through the loop formed by the needle. These bobbins must be wound with thread and may be wound when desired by the operator of the machine. This is usually accomplished by means of an attachment on the machine in which the bobbin to be wound may be mounted, and this attachment affords means for rotating the bobbin automatically when the machine is driven and has means for laying the thread on the bobbin. Such machines usually include means for supporting a spool of thread rotatably and under normal conditions the thread is guided from the spool to the needle bar of the machine. When it is desired to wind a bobbin the thread from the spool is not guided to the needle bar but is guided to the attachment referred to. With this arrangement, although the bobbin can be wound automatically by the mechanism, it necessitates additional labor in order to accomplish this result.

One of the objects of this invention is to provide means for effecting the automatic winding of a bobbin on a sewing machine without interfering in any way with the normal sewing operation of the machine; in other words to provide means for effecting simultaneously the normal sewing operation and the winding of the bobbin.

A further object of this invention is to provide very simple means for effecting the automatic winding of the bobbin.

A further object of the invention is to produce an attachment of very simple construction which can be readily secured on the machine so as to enable it to be used simultaneously to sew and to wind a bobbin.

The invention consists in the general combination of parts and details described in

the following specification, all of which contribute to produce an efficient sewing machine, while the broad scope of the invention is set forth in the appended claims.

In the drawing:

Figure 1 is a side elevation illustrating in outline the upper part of a sewing machine to which my invention is applied and indicating the manner in which the sewing is accomplished and the simultaneous winding of a bobbin.

Fig. 2 is a perspective showing one embodiment of a detail of the invention.

Referring more particularly to the parts, 1 represents a sewing machine table upon which a housing 2 is mounted and provided with the usual head 3 in which reciprocates a needle bar 4, the lower end of which carries a needle 5 through which the thread 6 is guided to form the stitches. Substantially all sewing machines of this type have at some point on the housing means for supporting a spool from which the thread 6 is supplied. This means usually consists of a horizontal seat or boss 7 formed on the housing and provided with an upwardly extending pintle 8 which is about as long as the length of an ordinary spool. The spool which is to supply the thread is simply placed on the boss 7, its bore being received over the pintle 8 so that the spool is rotatably supported. Such sewing machines also usually have at the point indicated a bobbin winding mechanism 9. This bobbin winding mechanism is usually of very simple construction involving a small worm 10 which may be rotated by means of a small belt pulley 11 which rests against the round belt 12 which drives the main spindle of the sewing machine. The worm 10 meshes with a worm wheel 14 carrying a cam 15, and as the cam rotates with the worm wheel it swings to and fro the thread laying arm 16 which is pivotally mounted at 17. A bobbin 18 may be detachably supported on the axis of the worm 10 so as to be rotated when the worm rotates. The thread 19 passes through a suitable guide 20 near the pivot 17 and then through a notch 21 at the end of the arm 16. According to my invention I provide means for simultaneously rotatably supporting two spools, one of which

supplies the thread 6 to the needle bar 4, and the other of which supplies the thread 19 to the bobbin winding mechanism. For this purpose I prefer to provide a spool 5 holder 22 having means for rotatably carrying two spools. The spool carrier is preferably in a simple form adapted to be attached to the pintle 8. For this purpose I prefer to construct a carrier with a socket 10 23 at one end, and this is preferably accomplished in a simple manner by forming the spool carrier of a simple split tube or spindle 24, preferably of resilient material such as steel or brass. The tube preferably has 15 a slot or slit 25 which extends longitudinally throughout its entire length. The lower or socket end 23 of the spindle 24 is adapted to fit neatly over the spindle 8, see Fig. 1, and should fit tightly so as to exert a resilient 20 grasp upon the pintle 8. At a suitable point on the spindle or tube 24 I prefer to provide means for supporting a second spool, which is preferably in the form of a plate or disk 26 which is rigidly attached 25 to the tube, transversely thereto.

It is understood that in using the device the lower spool 27 is placed on the pintle 8 and then the attachment 22 is placed in position, after which the upper spool 28 is 30 placed on the upper part of the spindle and supported on the guard 26. The thread 6 may be drawn off from the lower spool 27, while the thread 19 may be drawn off from the upper spool 28 and guided through the 35 bobbin winding mechanism. In practising my invention it is evident that the bobbin winding operation may be carried on simultaneously with the sewing operation. The bobbin winding attachment usually includes 40 some means not illustrated for throwing the pulley 11 out of contact with the belt 12.

Where the device is used with cotton thread, the part 26 may be in the form of a plain disk. If the device is used with silk 45 thread, there is a tendency for the silk thread to slip on the disk as it comes from the upper spool 28. If this happens, the silk thread, as it comes off the spool 28 runs around the edge of the disk and this tends 50 to entangle it with the thread 6 from the other spool. In order to overcome this, I prefer to provide some means for engaging the thread 19 and guiding it. This means preferably consists of a simple tooth or projection 55 29 which may, if desired, be formed integral with the disk 26 and simply bent up in some such manner as that illustrated in Fig. 2.

Since socket end 23 frictionally engages 60 and is supported by spindle 8, the position of the attachment on the spindle can be readily adjusted to locate plate or disk 26 at any desired relation to the upper end of the needle-supply spool, it being understood 65 that plate 26 is out of contact with

the spool in order that the spool may be free to rotate during the thread-drawing action. To illustrate, Fig. 1 shows the lower end of the attachment extending into the spool approximately half the spool length. Owing to the frictional engagement of tube and spindle, movements of the needle-supply spool during thread-drawing will not be communicated to the attachment and hence cannot affect the operation of the bobbin-supply spool; nor will the movements of the bobbin-supply spool affect the position of the attachment or cause its rotation. As a result neither spool can shift the position of the attachment, so that projection 29 will maintain the position in which it is placed and is unaffected in any manner, insuring proper guiding of the thread.

In practising my invention I do not limit myself to the use of all the novel features together, but I may use any of the novel features separately. It is understood that the embodiment of the invention set forth herein is only one of the many embodiments or forms the invention may take, and I do not wish to be limited in the practice of the invention nor in my claims to the particular embodiment set forth.

What I claim is:

1. The combination with a sewing machine head having a spool-holding spindle and a bobbin winder, of detachable means for supporting a bobbin-supply spool in substantially axial alinement with the needle-supply spool, said means comprising a split tube frictionally supported by the spindle and having an intermediate spool-supporting plate of greater diameter than the spool supported thereby and extending transverse to the axis of the tube, whereby sewing and 100 bobbin-winding operations may be had concurrently and movements of the needle-supply spool will be ineffective to produce plate movements.

2. The combination with a sewing machine head having a spool-holding spindle and a bobbin winder, of detachable means for supporting a bobbin-supply spool in substantially axial alinement with the needle-supply spool, said means comprising a tube 115 frictionally supported by the spindle and having an intermediate spool-supporting guard of greater diameter than the spool supported thereby, said guard carrying a thread guide at its outer edge, whereby sewing and bobbin-winding operations may be had concurrently and movements of either spool during operation will be ineffective to shift the position of the thread guide.

3. A spool support for sewing machines 125 having a spool-holding spindle and a bobbin winder, comprising a tube adapted to be frictionally supported by the spindle and having an intermediate spool-supporting guard extending beyond the base of the 130

spool supported thereby, said guard carrying a thread guide at its outer edge, whereby sewing and bobbin winding operations may be had concurrently, and movements of either spool during operation will be ineffective to shift the position of the thread guide.

In testimony whereof I have hereunto set my hand in presence of two subscribing witnesses.

RAY DOUGLASS.
